UNITED STATES PATENT OFFICE.

JOHN EASTON DALGLISH, OF SOMERVILLE, MASSACHUSETTS.

WALL-BOARD.

1,386,554.

Specification of Letters Patent.

Patented Aug. 2, 1921.

Application filed September 15, 1920. Serial No. 410,356.

To all whom it may concern:

Be it known that I, JOHN E. DALGLISH, a citizen of the United States, residing at Somerville, in the county of Middlesex and State of Massachusetts, have invented new and useful Improvements in Wall-Boards, of which the following is a specification.

This invention relates to facings for building walls generally known as wall boards, 10 and more particularly to devices of this kind in the form of a slab or tile.

The invention has for its object to provide a very strong and durable as well as a fire proof wall board, and one which has a 15 smooth surface and which will not warp.

The invention also has for its object to provide a wall board which is very simple and inexpensive, and which can be manufactured at the building site.

20 Other objects and advantages of the invention will be pointed out in the detailed description appearing hereinafter, and in order that the same may be better understood, reference is had to the accompanying drawing forming a part of this specification.

In the drawing,

Figure 1 is a plan view of the article, and Figs. 2 and 3 are cross sections on the 30 lines 2—2 and 3—3, respectively of Fig. 1.

Referring specifically to the drawing, the wall board is composed of a rectangular slab 5 of plastic material in which are embedded wooden strips 6. The material of which 35 the slab is made is a mixture of plaster of Paris, saw dust and marble dust to which a suitable quantity of water is added to produce a plastic mass which is molded and allowed to set until it assumes a hard mass.

40 The plastic composition is poured into the mold, a sufficient quantity being poured to produce a thin slab. A sheet of burlap 7 or other suitable rough reticulated binder material is then placed on top of the slab and 45 pressed down into the composition, after which the wooden strips 6 are placed on top of the burlap sheet, which latter is now pulled over the wooden strips along the sides of the slab, and short pieces of burlap 8 are spread

over the strips in the center. Additional plastic material is now poured into the mold to cover the wooden strips and the burlap, and the top of the mass is made level and smooth. After the plastic mass has hardened the top is polished to form the face of the 50 slab. The burlap embedded in the slab acts as a binder to hold the plastic composition together, and the wooden strips serve to reinforce the slab, and they are also employed for nailing purposes. It will be noted that 55 the slab is rabbeted at its edges so that when a number of slabs are assembled to produce a wall facing, they may be interlocked and a smooth joint between the slabs is made possible. It will be understood, however, 60 that any other type of joint may be employed. The wooden strips are positioned to lie in the rabbeted portions of the slab, and hence the heads of the nails driven therethrough are completely concealed. 70

A slab constructed as hereinbefore described is fire-proof and water-proof and also very strong and durable. The slabs can be nailed directly to the studding, and by applying some of the same plastic composition over the joints, and troweling the same 75 smooth, a perfectly smooth wall is obtained, all the joints being covered and thus concealed. The slabs may also be given an ornamental face and used for ceilings, and 80 no lathing or grounds are needed. A further advantage of a slab constructed as hereinbefore described is its cheapness, and the fact that it can be manufactured directly 85 at the building site, thus saving transportation expenses.

I claim:

A building unit composed of a slab of plastic material having rabbeted edges, wooden strips embedded in the body of the 90 slab and also in the rabbeted edge portions thereof, said edge strips running in the direction of the length of the edges of the slab, and a reticulated binder sheet around the strips, said sheet being also embedded 95 in the slab.

In testimony whereof I affix my signature:

JOHN EASTON DALGLISH.
